CLAIM

Aug. 12, 2015 (KR) 30-2015-0040726

The ornamental design for a wireless charger for electronic device, as shown and described.

(51) **LOC (10) Cl.** **13-02**

DESCRIPTION

(52) **U.S. Cl.**

FIG. 1 is a front perspective view of a wireless charger for electronic device, showing our new design;

USPC **D13/108; D13/103; D14/250**

FIG. 2 is a front view thereof;

(58) **Field of Classification Search**

FIG. 3 is a rear view thereof;

USPC D13/102-110, 118-119, 184, 199;

FIG. 4 is a left-side view thereof;

D14/356, 432, 251, 253, 434,

FIG. 5 is a right-side view thereof;

D14/203.3-203.8, 217, 248, 250, 252,

FIG. 6 is a top view thereof;

D14/440, 450, 496; D3/201, 218, 269,

FIG. 7 is a bottom view thereof; and,

D3/301, 273, 303

FIG. 8 is a rear perspective view thereof.

CPC Y02E 60/12; Y02E 60/122; Y02E 60/124;

The broken lines illustrating portions of the wireless charger for electronic device form no part of the claimed design.
